CLAIM

The ornamental design for a combination container and candle, substantially as shown and described.

DESCRIPTION

FIG. 1 is a perspective view of the combination container and candle showing my new design;

FIG. 2 is an exploded perspective view thereof;

FIG. 3 is an exploded top plan view thereof; and,

FIG. 4 is an exploded bottom view thereof.

In the drawings, the broken lines depict unclaimed subject matter only and form no part of the claimed design.
